UNITED STATES PATENT OFFICE.

IRVING SONNENTHAL, OF NEW YORK, N. Y.

HOOK-LATCH.

1,370,711.

Specification of Letters Patent.

Patented Mar. 8, 1921.

Application filed January 29, 1920. Serial No. 355,014.

To all whom it may concern:

Be it known that I, IRVING SONNENTHAL, a citizen of Poland, and a resident of New York city, borough of Manhattan, in the county and State of New York, have invented certain new and useful Improvements in Hook-Latches, of which the following is a full, clear, and exact description.

Among the principal objects which the present invention has in view are: to prevent the accidental releasing of a latch of the character mentioned; to afford a neat and workmanlike appearance; to strengthen the construction; and to simplify and cheapen the construction.

Drawings.

Figure 1 is a longitudinal view of a latch constructed and arranged in accordance with the present invention, the latch being shown in conjunction with the end fragments of a silk wristband, and in the open position;

Fig. 2 is a similar view showing the device in its closed position;

Fig. 3 is a side view of the device showing the parts as in the open position;

Fig. 4 is a view of the under side of the latch, showing the same on enlarged scale, and in the open position; and

Fig. 5 is an edge view showing the latch and wristband connected therewith in closed position.

Description.

The latch herein disclosed is particularly adapted for use with wristbands constructed of ribbon, or other flexible material. To this end one extremity of the ribbon 10 is permanently attached to a metal loop 11, the forward bar of which engages a service hook 12. The service hook 12 is slidably mounted within shield hook 13, formed integrally with a buckle body 14 the extremity of said hook being disposed in parallel relation to the buckle body 14. As seen best in Fig. 4 of the drawings, the body 14 has by design a series of grid bars 15, about and through which the looped end of the other extremity of the ribbon 10 is woven.

The shield hook 13 forms a guide for the hook 12 during the movement of the hook 12 lengthwise of the shield hook 13. In the normal position of the hook 12, as seen in Figs. 2 and 5 of the drawings, the extremity of the shield hook 13 serves as a guide for a hollow hood 16, within the hollow of which said shield hook enters and is housed.

Coöperating with the shield hook 13, to maintain the normal service relation of the hook 12, is a tongue that extends through a slot formed in the overturned bracket 18. 60 The bracket 18 is integral with the body 14, and with the shield hook 13, being preferably cut or punched from a single plate or sheet of metal.

In operation the hood 16 is drawn back 65 to uncover the end of the shield hook 13. In this operation the tongue 17 is extended through the slot 19, in which it rests, and the extremity of the hook 12 is drawn forward to approximately align with the extremity of the hook 13, as shown in Figs. 1 and 3 of the drawings. As the loop 11 has been disposed within the hook 12, it may now be removed therefrom, when the hood 16 and parts associated therewith are again 75 moved forward, until the said hood engages the extremity of the shield hook 13. By this arrangement the movable part, constituted by the hood 16, the hook 12, and tongue 17, is prevented from disarrangement or separation from the body 14 and parts associated therewith. When it is desired to again place the loop 11, or some other loop within the hook 12, the hood 16 is drawn back to the position shown in Fig. 3, to admit the said 85 loop, which then is employed to draw the hook 12 and parts associated therewith into the normal or closed position.

The latch may be used in many services. One service for which it is particularly fitted is for use on a bracelet for wrist watches. It will be observed that the normal tendency of the hood 16 and parts associated therewith is to assume the position where the latch is closed, and from which it is difficult 95 to remove by accident the loop 11.

Claims.

1. An article as characterized comprising a body portion having elongated fastening bars extending transverse said body portion in spaced parallel relation, said bars affording means for attaching a ribbon to said body in service relation, said body being further provided with a shield hook extended from the edge thereof and integrally formed therewith; a service hook adapted to fit within said shield hook, said service hook having a tubular hood integrally connected therewith, said hood being adapted for infolding in service said shield hook to prevent the dis-alinement of said service hook, 105

110

said hood being held by said service hook in spaced relation to said body portion for permitting the threading of said ribbon on said bars; and means integrally formed on 5 said body portion at the rear of said hood in line with said shield hook for partially supporting said hood when disengaged from said shield hook.

2. An article as characterized comprising 10 a body portion having elongated fastening bars extending transverse said body portion in spaced parallel relation, said bars affording means for attaching a ribbon to said body in service relation, said body being 15 further provided with a shield hook extended from the edge thereof and integrally formed therewith; a service hook adapted to fit within said shield hook, said service hook having a tubular hood integrally

connected therewith, said hood being adapted for infolding in service said shield hook to prevent the dis-alinement of said service hook, said hood being held by said service hook in spaced relation to said body portion for permitting the threading of 25 said ribbon on said bars; and means integrally formed on said body portion at the rear of said hood in line with said shield hook for partially supporting said hood when disengaged from said shield hook, 30 said means embodying a slotted bracket integrally formed with and upturned on said body portion, and a tongue integrally formed on said hood and extended from the rear thereof for engaging the slot in said 35 bracket.

IRVING SONNENTHAL.
